L. J. FOX

DEVICE FOR SECURING NAME PLATES

Filed July 5, 1923

INVENTOR:

Leonard J. Fox

BY

Allen & Allen

ATTORNEYS.

UNITED STATES PATENT OFFICE.

LEONARD J. FOX, OF CINCINNATI, OHIO.

DEVICE FOR SECURING NAME PLATES.

Application filed July 5, 1923. Serial No. 649,505.

To all whom it may concern:

Be it known that I, LEONARD J. FOX, a citizen of the United States, and a resident of Cincinnati, in the county of Hamilton and State of Ohio, have invented certain new and useful Improvements in Devices for Securing Name Plates, of which the following is a full, clear, and exact description, reference being had to the accompanying drawing, forming part of this specification.

The object of my invention is to provide a construction by which one plate can be readily and easily secured to another member, and it is especially designed for securing such name plates to the radiator shells of automobiles, in which the shell is usually constructed of comparatively thin sheet metal and a circular opening with an in-turned flange is usually provided in which the name plate is to be secured.

It is to be understood, however, that the construction is equally applicable for securing one plate to another where the receiving plate is sufficiently thick as not to require a flanged opening.

The invention consists of that certain novel construction and arrangement of parts to be hereinafter particularly pointed out and claimed.

30 In the drawings:

Figure 1 is a central section through opening in the securing plate with the name plate in place.

Figure 2 is an end view of the name plate.

Figure 3 is an inside rear view of the device as shown in Figure 1, and

Figure 4 is a detail section showing the method of securing the parts together.

A section of the sheet metal shell for an automobile radiator which I have selected for illustrative purposes is indicated at 1, with a circular opening therein provided with an inwardly extending flange 2.

The name plate 3 has secured to its back 45 a circular member 4 with a projecting flange 5 which flange is divided into sections by longitudinal cuts 6, so as to allow the flange members to be expanded slightly.

In order to press the flange sections outwardly, a dished, annular spring plate 7 is forced within the flange and the outer edge of the spring plate forces outwardly the outer edge of the flange sections to form a slightly curved enlargement 8, which is illustrated, somewhat exaggerated, in Figure

4. In order to hold the annular spring plate 7 in this position, I punch teats 9, 10, on the inside of the flange members so that a seat is provided for the spring plate 7 to lock it in position. Instead of this means 60 for securing the spring plate, beads might be formed on the flange members or some other well known method employed to lock the spring plate in place.

The spring plate is slightly larger in diameter than the diameter of the flange member into which it is inserted and the edge of the spring plate snaps past the outer row of teats and seats itself between that row and the inner row. The outer edge of the 70 spring plate, it will be understood, bears against the flange at a point just beyond the outer edge of the flange 2 of the plate 1, so that when the name plate is pushed into place the portion 8 will engage over the 75 edge of the flange 2 and thus will lock the name plate in position.

While I have illustrated the spring plate as a dished ring, it will, of course, be understood that the spring plate can be formed from a solid disk without any opening at the center and the parts may be so designed that such disk spring plate, whether solid or open, may rest centrally on the name plate, instead of finding a seat on the teats 9. 80

As the flange member 5 on the name plate is slightly larger than the diameter of the opening in the holding plate, there will be frictional contact between the two flanges, but the engagement of the part 8 over the 90 edge of the holding flange 2 locks the plates together. Of course, if the holding plate is of substantial thickness, then there will be no need of a flanged opening and the name or other plate to be attached will be locked 95 behind the edge of the opening.

Having thus described my invention, what I claim as new and desire to secure by Letters Patent, is:—

1. In a device of the character specified, 100 a holding plate with an opening therein, and a name plate to be secured thereto, the name plate provided with a flange and a separate annular spring plate to be inserted within the flange with the periphery of the spring plate bearing against the flange to form an external ridge therefor to engage behind the edge of the opening in the holding plate to lock the second plate thereto.

2. In a device of the character specified, 110

a holding plate with an opening therein, and a name plate to be secured thereto, the name plate provided with a flange divided into sections and a separate annular spring plate to be inserted within the flange members, with the periphery of the spring plate bearing against the flange members to form an external ridge therefor to engage behind the edge of the opening in the holding plate to lock the name plate thereto.

3. In a device of the character specified, a holding plate with a flanged opening

therein, and a name plate to be secured thereto, the name plate provided with a flange divided into sections and a separate annular spring plate to be inserted within the flange members, with the periphery of the spring plate bearing against the flange members to form an external ridge to engage behind the edge of the opening in the holding plate to lock the name plate thereto, and teats on the flange for holding the spring plate in place.

LEONARD J. FOX.
